UNITED STATES PATENT OFFICE

2,430,043

BASE FOR TILTING CHAIRS

Harry W. Bolens, Port Washington, Wis., assignor,
by mesne assignments, to The Seng Company,
Chicago, Ill., a corporation of Illinois

Original application August 3, 1940, Serial No.
350,310. Divided and this application March
15, 1944, Serial No. 526,515

3 Claims. (Cl. 248—194)

1

This invention relates to an improvement in tilting chairs, and more particularly to an improvement in the base of such chairs and in the chair iron which supports the seat on the base for tilting movement.

The present application is a division of my application for "Tilting chairs," filed August 3, 1940, Serial No. 350,310.

One of the objects of the invention is to provide a hub which may be fabricated from sheet metal parts, but which is extremely strong, rugged in assembly, durable, and comparatively inexpensive to manufacture.

Other objects and advantages reside in certain novel features of the construction, arrangement, and combination of parts, which will be hereinafter more fully described and particularly pointed out in the appended claims, reference being had to the accompanying drawing forming a part of this specification, and in which:

Figure 1 is a view in side elevation showing the metal base to which the legs are connected and upon which the spindle of the chair iron is supported;

Figure 2 is a view in transverse, vertical cross section taken on line 2—2 of Figure 3;

Figure 3 is a view in bottom plan of the metal base shown in Figures 1 and 2;

Figure 4 is a view thereof in transverse, horizontal cross section taken on line 4—4 of Figure 1; and

Figure 5 is a fragmentary view in section, taken on line 5—5 of Figure 3.

Referring to the drawing, the hub comprises a central sleeve or tube 6 which may be rolled from a piece of sheet metal and which has its upper ends flanged outwardly as at 7. A strengthening and reinforcing ring or cap 8 is disposed on the flange 7, and this ring or cap 8 is spun around the outer edge and under the margin of the flange 7, as indicated at 9. A circular top plate 10 is provided and has a central opening through which the tube 6 extends and to which the tube is snugly fitted. The margin of the opening of the top plate 10 is engaged with and supported by an outwardly directed corrugation 6' provided on the tube 6. A double-flanged sleeve or ferrule 10' surrounds the portion of the tube 6 located between the top plate 10 and its flange 7 and serves to hold the top plate against its corrugation and to stiffen and reinforce the flange 7. Leg-engaging brackets 12 are provided, and in the present instance there are four in number. They are of similar construction and each is of shallow V-

2

shaped formation in horizontal cross section, although at spaced intervals along the length of each the leg bracket ribs or bosses 13 are pressed out therefrom to stiffen and strengthen these brackets. The upper end of each leg bracket is provided with integral attaching lugs 14 which extend through suitable slots provided therefor in the top piece 10 and are upset into secure and rigid engagement with the top piece. The lower 10 end of each bracket plate is provided with a slot to adapt it to be interfitted and interconnected with the generally triangularly shaped attaching arm 15 provided therefor on the lower plate 16 of the hub. The plate 16 has a central opening 15 through which the tube 6 projects.

In the assembly the legs are disposed between the confronting portions of adjacent bracket plates and they are secured in this position by screws 18 which extend through openings provided in the top piece and are threaded into the legs. A hub construction of this character may be manufactured with facility and at comparatively little expense from sheet metal, and yet provides an extremely strong and rugged construction and one which will stand up over a long period of time.

In manufacturing the hub of the base the tube 6 is first formed into a cylinder with its upper end unflanged. The corrugation 6', usually an interrupted corrugation, is then formed. The top plate 10 is then assembled with the tube, the previously flanged ferrule 10' slipped over the upper end of the tube, the upper end of the tube 6 flanged outwardly, and the reinforcing plate 8 then assembled with these parts and spun into place. The leg brackets and bottom plate are then assembled with the other elements.

While I have shown and described one construction in which the invention may be advantageously embodied, it is to be understood that the construction shown has been selected merely for the purpose of illustration or example, and that various changes in the size, shape, and arrangement of the parts may be made without departing from the spirit of the invention or the scope of the subjoined claims.

I claim:

1. A hub for the base of a tilting chair comprising a centrally disposed tube having its upper end flanged outwardly, a double flanged ferrule on said tube, a reinforcing cap formed over said flanged upper end on the tube and a flange on said ferrule, a corrugation on said tube, a top plate rigidly interconnected with the tube and

held between said corrugation and the other flange of said ferrule, leg brackets having lugs staked to the top plate, and a bottom plate having attaching arms interfitting with the lower ends of the leg brackets and staked thereto.

2. A hub for the base of a tilting chair comprising a central tube having its upper end flanged upwardly, a reinforcing cap having an upper portion formed over said flanged upper end of the tube to provide a bearing member for receiving the thrust forces placed on a chair spindle carried by said hub and a lower portion formed under said flanged upper end of the tube to hold said cap in position, a top plate interconnected with the tube adjacent its upper end, a bottom plate mounted on the lower end of the tube, and leg brackets extending between and secured to said plates.

3. A hub for the base of a tilting chair comprising a central tube, a top plate rigidly interconnected with and supported on the upper end portion of the tube, a bottom plate mounted on the lower end of the tube, and leg-engaging

brackets having sides forming a shallow V-shaped cross section extending between said plates, the confronting sides of adjacent brackets forming a socket for receiving a respective leg, said leg brackets having their upper ends fastened to the top plate, said leg brackets having their lower ends slotted at the vertex, said bottom plate having triangularly shaped attaching arms the sides of which engage the sides of a respective leg-engaging bracket to provide backing therefor and to prevent separation of said confronting sides, said arms being connected to said bottom plate by portions received in said slots.
